UNITED STATES PATENT OFFICE.

THOMAS J. McCAFFREY, OF SPOKANE, WASHINGTON, ASSIGNOR OF ONE-HALF TO
GEORGE H. LIBBY, OF SPOKANE, WASHINGTON, AND ONE-SIXTEENTH TO ALFRED
E. REED, OF SAN FRANCISCO, CALIFORNIA.

SIPHON-VALVE FOR FLUSH-TANKS.

1,258,232.

Specification of Letters Patent.

Patented Mar. 5, 1918.

Application filed February 20, 1917. Serial No. 149,856.

To all whom it may concern:

Be it known that I, THOMAS J. McCAFFREY, a citizen of the United States, residing at Spokane, in the county of Spokane and State of Washington, have invented certain new and useful Improvements in Siphon-Valves for Flush-Tanks, of which the following is a specification, reference being had to the accompanying drawings.

10 This invention relates to flush valves and more particularly to valves which include a siphon.

The general object of this invention is to provide very simple and easily operated means for starting the siphoning action and a further object is to provide a starting valve so constructed that only a slight action of the valve is necessary in order to start the siphon but in which the valve will move to a position where it will not obstruct the passage of water through the siphon.

20 A further object of the invention is the provision of a valve and siphon combined so constructed that it may be placed as a unit within the flush tank and very easily engaged therewith or disengaged therefrom.

Other objects will appear in the course of the following description.

25 My invention is illustrated in the accompanying drawings, in which:

Figure 1 is a longitudinal sectional view through a flush tank and through the combined valve and siphon;

Fig. 2 is a section on the line 2—2 of Fig. 1;

Fig. 3 is a fragmentary vertical sectional view of a tank, with a modified form of valve mechanism therein, and showing the tank connected to a closet bowl, the bowl being partly in section;

Fig. 4 is a section on the line 4—4 of Fig. 8; and

Fig. 5 is a section on the line 5—5 of Fig. 3.

45 Referring to these drawings it will be seen that my improved valve comprises a cylindrical chamber 10 open at its lower end and having a siphon leg 11 extending from its upper end at one side. One wall of this siphon is formed by the extension 12 of the side wall 13 of the chamber 10. In other words, the pipe which forms the siphon is preferably integral with the wall of the chamber 10. The siphon extends down be-

low the lower end of the chamber 10 in the form of a pipe 14 and has mounted upon it the collar 15 and below this collar is exteriorly screw-threaded for engagement with a collar 16. These collars 15 and 16 form clamping collars which engage the bottom 60 of the flush tank between them.

Disposed through the top of the chamber 10 is a pull rod 17 which at its upper end is connected to a chain pull 18 or any other suitable appliance whereby the rod may be lifted. The lower end of the pull rod carries upon it a spider formed of radiating arms 19 and resting upon this spider is the lifter 20. This lifter consists of a disk of leather or other suitable material and 70 loosely surrounds the pull rod 17 so that it may be easily shifted thereon. Normally this disk 20 rests upon the radiating arms and is supported thereby so that when the rod is lifted the disk 20 will be lifted with 75 it. When the rod 17 falls, however, if there is any obstruction to the downward movement of the lifter 20 due to the upward movement of water within the chamber 10, then the lifter will remain in the upper portion of the chamber.

The operation of this invention is as follows: Normally the tank 21 within which the lifter is disposed is filled with water to the upper end of the siphon legs, that is 85 just below the upper end of the partition 12 separating the two legs. The lifter is normally in the position shown and if the rod 17 is pulled upward, the lifter 20 will lift the water which is above the lifter upward, 90 thus forcing the water from the leg 11 of the siphon into the opposite leg and starting the siphon action. The water in the tank will promptly rush into the lower end of the chamber 10 and the inrush of water 95 will carry the lifter 20 up so that it will rest against the upper end of the chamber 10. Under these circumstances the arms 19 will of course offer no resistance to the free passage of water and the water will be 100 siphoned off in the usual manner. When the water has been siphoned from the tank and the tank is emptied, then the lifter 20 will drop and rest again upon the arm 19.

In the operation of this device, just as 105 soon as the water starts to flow over the partition in the siphon, the force of the water will raise the lifter plate or disk 20 and

will hold it up against the top of the chamber 10 but permitting the lifting rod 17 to drop back into its proper place. It is to be noticed that the entire valve is immersed 5 in water with the exception of the top of the siphon proper. With this construction when the water is flowing into the tank it will force all of the air out of the siphon up to the highest water level. This makes it 10 absolutely certain that the siphon will operate every time the chain 18 is pulled.

It will also be noticed that with this construction the combined siphon and valve is very readily put in place by simply inserting 15 the lower end of the pipe 14 through the opening in the bottom of the tank until the collar 15 rests upon the bottom of the tank and then screwing on the collar 16 and screwing this collar up tightly against the 20 bottom of the tank. This will prevent the water from leaking from the tank and is very easily adjusted. It is obvious that 25 gaskets may be used between the clamping collars. It will also be obvious that this construction is very simple and that it is not liable to get out of order and that there are very few parts to wear so that the valve 30 will last for a long time.

In Figs. 3 and 4, I have shown a modified form of the valve shown in Figs. 1 and 2. In this form of the invention there is provided a chamber 22, which is the equivalent of the chamber 10, heretofore described, which chamber 22 is open at its lower end 35 and has a siphon 23 extending from its upper end. The inner or shorter leg 24 of this siphon is not offset from the chamber 22, as it is in Fig. 1, but the inner wall of the leg 24 is approximately in the same plane as the 40 corresponding wall of the chamber 22, thus providing for a freer flow of the water from the chamber 22 into the leg 24 of the siphon. Disposed within the chamber 22 is a lifter 45 25 which has an area approximately the same as the cross sectional area of the chamber 22. As illustrated, this chamber 22 is rectangular in cross section and the lifter plate 25 is also rectangular in cross section. Supporting the lifter 25 and extending 50 loosely through it is the stem or rod 26 which extends upward through the upper end of the chamber 22 and is connected by a chain 27 to the ordinary means for flushing the closet.

55 That portion of the lifter plate below the leg 24 is cut away as at 28, and hinged to the lifter plate 25 is a small flap valve 29, which is disposed upon the upper face of the lifter 25, and is slightly longer than the opening 28 so that when this auxiliary valve 29 is in a horizontal position, it will rest at its ends 60 upon the margins of the opening 28, as shown most clearly in Fig. 4. Now when the lifter 25 is raised, it will act precisely 65 in the same manner as the lifter 20 hereto-

fore described and raise the water above the lifter with it so as to start the siphoning action. As soon as the lifter 25 has been drawn to the upper end of the chamber 22, however, and the siphon is started, then the 70 upward movement of the water will lift the flap valve 29 to the position shown in Fig. 3 and the water will siphon out through the siphon in the same manner as heretofore described, until the tank is emptied, whereupon the auxiliary valve 29 will again close. This construction permits the lifter rod 26, after it has been raised and the siphoning 75 action started, to be dropped to its original position and the uprush of the water will hold up the lifter 25 and keep the auxiliary valve 29 raised until the contents of the tank have been siphoned away. I have illustrated in Fig. 1 a cylindrical chamber 10 and in Fig. 3 I have illustrated a rectangular chamber 80 22 and it is to be understood that I do not wish to be limited to any particular form for the chambers 10 or 22.

In Fig. 3, I show the valve in connection with a closet bowl and trap and in connection with the usual water controlling valve disposed in the flush tank and controlled by a float. The pipe A leading from the leg 14 of the siphon extends downward to the bowl B having the usual closet trap C. The valve 90 for admitting water to the flush tank is designated D and this valve is controlled by a float rod E having the float F thereon. Now when the chain 27 is pulled, the water in the tank 21 will pass out through the siphon and 95 be discharged into the bowl B and the water running through the closet siphons the water from the closet trap C. It is therefore necessary to replenish this water in the closet trap and to this end a pipe G is connected 100 to the valve casing D and extends up and opens into the upper end of my improved siphon, preferably at the upper end of the long leg of this siphon. When the tank 105 21 is empty the float F drops down and opens the water supply valve allowing water to run through the flush tube or pipe G, while the tank is filling this water passing through the pipe G, flowing downward through the long leg of the siphon and thus filling the 110 closet trap with water. Thus by the time the tank 21 is filled, the closet tank is also filled. 115

While I have illustrated what I believe to be one of the best forms of my invention, I do not wish to be limited to the details of construction as it is obvious that these may be varied in many details without departing from the spirit and scope of the appended claims.

Having thus described my invention, what 125 I claim is:

1. A flushing siphon having an inlet leg and a chamber operatively connected to the inlet leg of the siphon, the inner wall of the inlet leg extending below the top of the 130

chamber and the outer wall of the inlet leg terminating at the top of the chamber, a stem movable vertically through said chamber and extending straight upward for its entire extent, and a lifter plate loosely mounted on the stem for vertical movement upward independent of the stem for the entire length of said chamber, to thereby pass the lower end of the inner wall of the inlet leg, the stem having independent movement downward relative to the lifter plate and having a stop on its lower end upon which the lifter plate normally rests.

2. As an article of manufacture, a siphon valve comprising a body open at its lower end and forming a chamber, a siphon having its inlet leg connected to the upper end of the body and having its outlet leg extended down below the body, a stem passing through the upper end of the chamber, a

lifter plate loosely mounted upon the stem and having free movement thereon for the entire length of the stem, said stem having a stop at its lower end supporting the lifter plate when the latter is in its lowered position, the lifter plate having an opening disposed in approximate alinement with the inlet leg of the siphon, and an auxiliary valve normally resting upon the upper face of the lifter plate, closing by pressure from above, but opening by pressure from below and adapted to permit the passage of water into the inlet leg of the siphon when the lifter has been raised to its full extent.

In testimony whereof I hereunto affix my signature in the presence of two witnesses.

THOMAS J. McCAFFREY.
